Ms. 1733

B. C. Cromwell, of Skowhegan, Me.
assor. to.

himself, S. D. Greenleaf, C. J. Douglass,
And R. C. Douglass, of same place.

Letters Patent No. 1733, dated Mch. 10. 1863.

The schedule referred to in these Letters Patent and making part of the same.

To all whom it may concern:

Be it known that I, B. C. Cromwell, of Skowhegan, in the County of Somerset, and State of Maine, have invented a new and original Design for a Pump Top; and I do hereby declare that the following is a full, clear and exact description of the same, reference being had to the accompanying drawings making a part of this specification, in which.

Figure 1, is an elevation of a pump top, showing my design.

Figure 2, a horizontal section of the same, taken in the line x, x, Figure 1. Similar letters of reference indicate corresponding parts in the two Figures.

This design relates to a cast metal pillar or chamber to which a discharge nozzle and pump handle is attached and which forms the exposed portion of a submerged pump, and is commonly termed a pump top.

This top is composed of a conical portion A, the lower part a, of which has a smooth exterior and an ovoli bead b, around its upper edge.

The other part c, of the portion A, which is the chief or main part of the pump top inflated nearly its whole length as shown at d, in both Figures.

The upper end of the conical portion A, has a cap B, upon it which is formed of a scotia e, fillet f, torus g, fillet h, and a scotia i, surmounted

Ms. 1733

by a dotted sphere j.

C, is the nozzle of the pump top, the inner part k, of which has a horizontal position and the outer part l, curved downward as shown in Figure 1. This nozzle is of circular form in its transverse section is slightly tapered and provided with an ovals head m, at its outer end.

Having thus described my invention, what I claim as new and desire to secure by Letters Patent, is.

The configuration of the parts herein shown and described to form a new and original design for a Pump Top.
